UNITED STATES PATENT OFFICE.

CHARLES H. URQUHART, OF NEWARK, NEW JERSEY.

FUEL.

1,386,473.

Specification of Letters Patent.

Patented Aug. 2, 1921.

No Drawing. Original application filed September 23, 1919, Serial No. 325,771. Divided and this application filed October 28, 1920. Serial No. 420,274.

To all whom it may concern:

Be it known that I, CHARLES H. URQUHART, a citizen of the United States, residing in the city of Newark, in the county of 5 Essex and State of New Jersey, have invented certain new and useful Improvements in Fuels, of which the following is a specification.

The present invention relates to fuels, and 10 more particularly to the kind of fuel produced by the process described and claimed in my copending application filed September 23, 1919, Serial No. 325,771, of which this application is a division.

15 Certain substances herein called low grade coals comprising particularly lignite and also such substances as peat and the like are unsatisfactory for use as fuels in the condition in which they come from the deposits.

20 The high volatile content is productive of smoke and the presence of the light volatile matter and water causes rapid disintegration, both when the lignite (which is hereinafter used as illustrative of all low grade

25 coals) is stored and during combustion. This tendency to disintegrate causes the lignite to crumble so rapidly in the fire box that a large percentage of it falls unburnt through the fire grates and is thereby lost.

30 It has been proposed heretofore to treat such low grade coals as lignite so as to prevent them from disintegrating both in storage and during combustion. To this end, lignite has been briqueted, but it has

35 been found that unless the volatile substances have been removed before briquetting, the disintegrating characteristics still remain to a large extent. And on the other hand, where the lignite is retorted or car-

40 bonized and the disintegrated or crumbled substance obtained therefrom is briqueted, much difficulty has been experienced in providing binders which will be constant in analysis so as to produce boulets and bri-

45 quets consistent in weathering qualities. Moreover, the cost of apparatus for briquetting is relatively large. Consequently, the making of briquetted fuel from substances such as lignite and other low grade coals, is 50 not at present a commercial proposition of any great moment.

The object of the present invention is to produce from low grade coals such as lignite and the like, a fuel which will have the ap-

pearance, qualities and burning characteristics of hard coal. This prepared fuel is produced without converting the lignite or other low grade coals into boulets or briquets. The crude lump lignite is treated in the condition in which it comes from the 55 mine and is preserved whole in its lumpy condition so that the fuel prepared from the raw material is kept substantially in the original lump form. This prepared fuel will not disintegrate either in storage or 60 during combustion and can be handled like ordinary hard coal with but little crumbling. The process by which the fuel is produced can be practised in one retort or container with no further handling than is necessary to charge it into the retort and to 65 discharge it therefrom upon the completion of the process. The apparatus used for producing the improved fuel may, therefore, be simple and inexpensive and the process 70 used may be carried on at small cost comparatively to the value of the product.

The improved fuel of the present invention is a low grade coal which has been treated in lump form to open up cracks or 75 interstices therein so that a suitable binder may be introduced into the coal, after which the coal and binder are fused together and carbonized. One method or process of producing the fuel of the present invention is described and claimed in my said application. It will be understood, however, that other methods or processes may be employed for producing the fuel, the object being to so treat the lignite or other 80 low grade coal that it will continue in substantially its original form and yet have all the characteristics of a high grade hard coal which may be handled and burned without liability of crumbling. A convenient process for producing the improved fuel is to inclose lumps of lignite or other low grade coal in a suitable retort and raise the temperature of the retort so as to drive off a portion of the water content from the lignite and some of the lighter volatile matters and continue this step until cracks appear 85 in the lignite. Into the cracks there is introduced a suitable binder such as melted pitch. When the binder has become sufficiently viscous to have a binding effect, the temperature of the lignite is raised sufficiently to drive off the remainder of the 90

95

100

105

water content and such of the volatile matters as can be driven off under the melting point of the pitch. When the lignite has been deprived of all of its hygroscopic wa-
5 ter so that there is no longer any liability of it disintegrating under heat, the temperature of the retort is rapidly raised until the lignite and the binder fuse together and carbonize. With some lignites it has been
10 found necessary to repeat the steps of introducing the binder and fusing.

By opening up cracks in the low grade coal and introducing a suitable binder into the cracks and then fusing the binder and
15 low grade coal together and thereby carbonizing them, a prepared fuel is produced which is consistent in weathering qualities, which is difficultly friable, and which will not unduly crumble either in handling or
20 in the fire box.

The fuel of the present invention is a low grade coal such as lignite and the like, which has been devolatilized, fused and welded together without briquetting and then
25 carbonized. As a result of this treatment it is anthracite-like and burns slowly and without smoke. It will therefore be recog-

nized that it may be produced by processes other than that outlined above.

Having thus described the invention, what 30 I claim as new is:

1. As an article of manufacture, a fuel made from low grade lignitic coal and a binder fused together, said fuel being in substantially the lump form in which the 35 coal comes from the deposit.

2. As an article of manufacture, a hard anthracite-like fuel made from low grade lignitic coal and a binder, said fuel being in substantially the lump form in which the 40 coal comes from the deposit.

3. As an article of manufacture, a difficultly friable and carbonized fuel made from low grade lignitic coal and a binder, said fuel being in substantially the lump 45 form in which the coal comes from the deposit.

4. As an article of manufacture, a fuel made from low grade lignitic coal and a carbonizable binder, said fuel being carbonized and in substantially the lump form in which the coal comes from the deposit. 50

CHARLES H. URQUHART.
